MEANS FOR CONTROLLING DENSITY OF
INSULATING MATERIALHarry Vroman Smith, Newark, Ohio, assignor to
Owens-Illinois Glass Company, a corporation
of Ohio

Application August 13, 1935, Serial No. 36,041

6 Claims. (Cl. 302—35)

My invention relates to apparatus for blowing insulating material such as mineral wool, nodulated glass wool and the like into confined spaces, for insulating or other purposes. More particularly, the invention relates to valve mechanism for automatically controlling the volume and pressure of air supplied with the insulating material, and thereby controlling the density or compactness of the material and consequently the number of square feet or area that can be covered to a desired thickness with a given weight of material.

At the present time, blowing machines are commonly used for blowing insulating material into the insulating spaces within the vertical walls and partitions of buildings and between the ceiling rafters, or in other confined spaces. The patent to Games Slayter, 1,728,837, September 17, 1929, Method of heat insulating, discloses a method of blowing insulating material into the walls of a building for the purpose above indicated.

The insulating material may consist of granulated or nodulized mineral wool, glass wool, or other compressible material in a more or less loose or fluffy condition. I have found that the amount of insulating material required for coverage of a given area when the material is introduced by means of a blower as above indicated, depends largely upon the relative amount of air and insulating material discharged from the blower and also on the air pressure or force of the blast. The blast pressure affects both the force of discharge and packing and also the relative amount of air and insulating material discharged from the apparatus. The pressure and velocity of air has a tendency to "puff out" the nodules and increase the ratio of air to insulating material.

For example, in blowing granulated or nodulated wool into the open spaces between ceiling rafters, I have found it desirable to maintain a relatively high ratio of air volume to volume of wool, so that as the material is discharged from the end of the hose the velocity of the air has a tendency to "fluff out" the nodules and deposit them between the rafters at a relatively low density. Thus, a comparatively large number of feet can be covered to the desired thickness with a given weight of material. On the other hand, a low volume of air has a tendency to pack the nodules as they move through the hose and to deposit them in a more compact shape in the insulating space between the rafters.

I have also found that in blowing the same material into the closed spaces between the ver-

tical studding of a building and in similar situations, a large volume of air is undesirable because it has a tendency not only to deposit the material in the partition or insulating spaces at too high a velocity, but also tends to build up a static pressure within the space being insulated. The material is thus compressed to a relatively high density. In these situations I have found it desirable to employ a comparatively low volume of air relative to the amount of insulating material so that the material drops gently from the end of the hose into the space beneath.

An object of my invention is to provide means by which the volume of air supplied from the blower relative to the amount of insulating material intermixed therewith, and also the air pressure, may be adjustably regulated and controlled in a manner to obtain the most economical and efficient application of the insulating material when applied under the varying conditions above indicated.

A further object of the invention is to provide, in combination with a blower of the type indicated, an automatically operated control valve or bleed valve by which a certain amount of air is permitted to escape in a manner to reduce and control the volume and pressure of air supplied through the nozzle with the insulating material.

A further object of the invention is to provide a control valve which will automatically close in the event of the discharge nozzle becoming clogged with insulating material, and thereby cause the pressure to rise and clear the nozzle.

Other objects of the invention will appear hereinafter.

Referring to the accompanying drawings:

Fig. 1 is a perspective view of a blower mechanism adapted for use in practicing my invention.

Fig. 2 is a sectional elevation of the relief valve by which the air pressure is regulated.

Fig. 3 is a top plan view of the blower mechanism, the hopper being omitted.

Fig. 4 is a fragmentary sectional elevation through the feeder and hopper.

The blowing machine may be of conventional construction and, as herein shown, comprises an air blower 10 which may be of the positive displacement type, and a feeder 11. The feeder comprises a rotor 12 mounted on a drive shaft 13 and rotated thereby within a cylindrical casing 14. An integral downward extension 15 of the casing provides a chamber or channel 16 extending lengthwise of the feeder.

The insulating material 17 is supplied to the feeder 11 from a hopper 18 mounted over the

feeder and having an opening 19 in the floor thereof through which the material is discharged into the feeder. The insulating material is herein shown in the form of nodules which may consist of loosely matted fibers of glass wool, mineral wool or other material. Air under pressure is conducted from the blower 10 through a pipe line 20 to the chamber 16 where it is mixed with the insulating material 17 which is being discharged by the feeder into the said chamber. The mixture of air and insulating material is transmitted under pressure from said chamber through a hose 22 to a nozzle 23 from which it is discharged.

The air pressure within the pipe line 20 is regulated and controlled by a bleeder valve mechanism 25 connected to the pipe line through a pipe extension 24. The pressure in the line is regulated in accordance with the resistance set up by the material to be discharged. If the resistance is raised as by clogging, the pressure in the line is automatically raised above the normal predetermined pressure, and when the resistance is lowered, the pressure is accordingly automatically reduced. The valve mechanism includes a casing comprising an upper end section 26, a lower end section 27, and an intermediate section 28 in the form of a tube or pipe having screw threaded connection with said end sections. A cup-shaped valve 30 is mounted within the valve casing, on the lower end of a vertical valve stem 31. The valve is adjustable vertically on the valve stem by means of adjusting nuts 32 and 33. The valve stem extends upward through and beyond an opening in the upper section 26 of the valve casing, the upper portion 34 of the stem being screw threaded.

The valve when in its lifted or full line position shown in Fig. 2, seats on a gasket 35 and closes a port 36 opening to the outside air. When the valve is lowered to the dotted line position, it opens communication from the pipe 24 through port 36 to the atmosphere. Adjustable stop nuts 37 threaded on the screw threaded section 34 of the valve stem, adjustably limit the downward or opening movement of the valve.

When it is desired to operate the blowing mechanism with the air at low pressure, the valve is held in its lowered or open position by gravity, thereby permitting a restricted escape of air through the port 36 by which the air pressure through the pipe line 20 is regulated and controlled. By adjusting the nuts 37, the amount of air admitted may be adjustably varied.

If the discharge pipe 22 or nozzle 23 should become clogged with the insulating material, due to the low pressure, a back flow of air through the extension 24 is induced and a back pressure built up which operates to lift and close the valve 30. This results in an increased back pressure sufficient to clear the pipe line. The amount of back pressure necessary to close the valve is adjustably regulated and controlled by means of weights 38 removably mounted on the valve stem. By removing one or more of these weights, there is a corresponding reduction in the amount of back pressure needed to close the valve.

It will be seen that the valve operates as a bleeder to maintain a comparatively low air pressure through the discharge nozzle when a low pressure is desirable, as, for example, in feeding insulating material downward into the vertical walls of a building. At the same time, the valve mechanism operates automatically to permit any increased pressure necessary to clear the dis-

charge pipe in the event it becomes clogged with the insulating material.

When a comparatively high discharge pressure is desired, as, for example, when the insulating material is being introduced in the space between an attic floor and the ceiling therebeneath, the valve 30 may be adjusted by means of the adjusting device 37 so as to remain closed or to restrict the exit of air through the port 36 to any desired extent. This permits the pressure at the nozzle 23 to be maintained as high as desired up to the full capacity of the blower.

The blower may be directly connected to a driving motor 40 through a drive shaft 41. The latter may also have a driving connection through speed reduction gearing 42 to the feeder shaft 13.

Modifications may be resorted to within the spirit and scope of my invention.

I claim:

1. Apparatus for introducing an insulating material into a confined space, comprising a blower, a nozzle, an air line extending between the blower and the nozzle, mechanism for introducing insulating material into said line and causing it to be discharged through said nozzle, and means for varying the ratio between the volume of air and insulating material discharged through the nozzle, said means including valve mechanism comprising a port opening from said air line to the outside atmosphere, a valve controlling said port, means for normally holding the valve in open position to permit the escape of a predetermined amount of air through said port, and means for adjusting the valve and thereby adjustably varying the amount of said escaped air, said valve capable of being closed by excess back pressure.

2. Apparatus for introducing an insulating material into a confined space, comprising a blower, a nozzle, an air line extending between the blower and the nozzle, mechanism for introducing insulating material into said line and causing it to be discharged through said nozzle, and means for varying the ratio between the volume of air and insulating material discharged through the nozzle, said means including valve mechanism comprising a port opening from said air line to the outside atmosphere, a valve controlling said port, and means for normally holding the valve open and permitting it to be closed automatically by an abnormal pressure built up in said air line.

3. Apparatus for introducing an insulating material into a confined space, comprising a blower, a nozzle, an air line extending between the blower and the nozzle, mechanism for introducing insulating material into said line and causing it to be discharged through said nozzle, and means for varying the ratio between the volume of air and insulating material discharged through the nozzle, said means including valve mechanism comprising a port opening from said air line to the outside atmosphere, a valve controlling said port, means for normally holding the valve open and permitting it to be closed automatically by an abnormal pressure built up in said air line, and means for adjustably varying the resistance of the valve to closing movement and thereby determining the amount of back pressure required to close the valve.

4. Apparatus for introducing compressible insulating material into a confined space comprising a blower, a discharge nozzle, an air line extending from the blower to the nozzle, a mixer by which the material is intermixed with the air passing through said air line, means providing a port opening in communication with the air line,

a bleed valve controlling said port opening, and means for yieldably holding the valve normally open to bleed a predetermined proportion of the air from said blower, said valve being movable 5 to closed position under a predetermined back pressure within the air line.

5. Apparatus for introducing compressible insulating material into a confined space comprising a blower, a discharge nozzle, an air line extending from the blower to the nozzle, a mixer by which the material is intermixed with the air passing through said air line, means providing a port opening in communication with the air line, a bleed valve controlling said port opening, means for yieldably holding the valve normally open, said valve being movable to closed position under a predetermined pressure within the air line, and adjusting means by which the open position of the valve may be adjustably va-

ried and the port opening throttled to any desired extent.

6. Apparatus for introducing insulating material into confined spaces, which comprises blowing mechanism, means for mixing the insulating material with air supplied by the blowing mechanism, means providing an air line between the blowing mechanism and the mixing means, valve mechanism comprising a port communicating with the air line, a valve controlling said port, 10 said valve movable by gravity to an open position and movable by pressure within the air line to closed position, means for adjustably regulating the open position of the valve, and adjusting means for adjustably varying the resistance offered by the valve to said closing movement. 15

HARRY VROMAN SMITH.
